GUN BREECH

Jaroslav Hásek, Prague, Czechoslovakia, assignor
to firm Limited Company formerly the Skoda
Works, Pilsen, Prague, Czechoslovakia

Application March 8, 1935, Serial No. 9,946
In Czechoslovakia March 8, 1934

1 Claim. (Cl. 89—22)

This invention relates to a gun-breech in which a system of screw threaded parts is employed, that is to say a nut and a spindle which, when the breech is closed, occupies a position in which its geometrical axis coincides with the geometrical axis of the bore of the gun barrel. This position will hereinafter be referred to as the axial position. In order to complete the closure of the breech in the axial position the threaded spindle is screwed out of the nut until an axial pressure is developed which is sufficient to effect the tight closure of the gun.

To open the breech, the spindle is first screwed into the nut, and then this system of screw threaded parts is shifted into a position which completely discloses the breech aperture, that is to say in which the breech is fully opened for re-loading. The intrusion of the spindle into the nut on opening, and the withdrawal of the spindle from the nut on closing the breech is effected by a rotary movement of one of the two elements of the screw threaded system of parts when in the axial position. Thus, either the nut rotates while the spindle is locked against rotation and merely moves axially, or the spindle rotates in a fixed nut in which case the spindle is axially displaced simultaneously with its rotation.

The shifting of the screw breech could be effected either by rectilinear displacement or by rectilinear rolling movement. In accordance with the present invention, however, the shifting of the breech system from the loading position to the axial position is effected on an arcuate path with the aid of members which are positively controlled by guiding means.

Forms of construction embodying the invention are shown by way of example and in diagrammatic form in the accompanying drawing, in which:

40 Fig. 1 is a longitudinal section of one form of construction of the breech according to the invention.

Fig. 2 is a section taken on the line II—II of Fig. 1.

45 Fig. 3 shows the breech screw alone, in elevation, as seen from the forward end, that is to say from the top in Fig. 1.

Fig. 4 shows, in longitudinal section, a modified form of construction of the invention which is of very special significance.

50 Fig. 5 is a substantially longitudinal sectional view of the coupling elements of a closure device according to Fig. 1, the view being illustrated on an enlarged scale, and

55 Fig. 6 is a substantially longitudinal sectional

view of the coupling elements of a closure device according to Fig. 4, the view being illustrated on an enlarged scale.

Referring to Fig. 1, the breech nut 10, together with the screw spindle 11, is held in a spring holder or rim 12 which is carried by the lower part (as viewed in Figure 1) of a hub 12' of square cross-section fitting over the squared upper portion 13 of a rocking shaft 15. Extending from the upper part of the hub 12' is a band 14 of polygonal shape which engages over the inner end of the spindle 11, said inner end being similarly shaped. This locks the spindle 11 against rotation and, as a result, when the breech nut 10 is rotated, the spindle 11 moves only axially.

In order to prevent unintentional rotation of the nut 10, the holder 12 is resilient, preferably in the form of opposed spring arms, as shown most clearly in Figure 2, whereby there is always an adequate frictional resistance between these arms and the nut 10.

The shaft 15 is rotatably mounted in the body 16 of the gun barrel, and carries at its outer end a lever 17 terminating in a projecting pin 18, which may be in the form of a roller, or the like. In the body of the gun barrel 16 there is axially mounted a cam plate 19 which is provided with a crank-handle 20. This plate 19 merges in the middle with a hollow screw spindle which is screwed into a threaded socket 21 formed in the body 16 of the gun-barrel. Loading is effected through the middle of this screw spindle. When the crank-handle 20 is operated in the one direction of rotation, the cam plate 19 is retracted bodily, and conversely, is intruded when the handle is turned in the opposite direction. In the plate 19 there is provided a groove 22 (see Fig. 3) engaged by the end 18 of the above-mentioned lever 17. This groove is provided with a cam portion, whereby at a certain point in the rotation of the plate 19, the rocking member 13 is pivotally moved through an angle α which is required to swing the breech assembly from the axial position into the open position for loading.

During the time that the breech spindle 11 moves axially in the nut 10, a concentric portion of the above-mentioned groove is in engagement with the pin or roller 18, and, therefore, no pivotal movement of the rocking member 13 takes place. The pin or roller 18 is, however, ultimately forced to one side by the cam portion of the groove 22, and this swings the breech assembly, including nut 10 and spindle 11, bodily into the dot-and-dash position of Figure 2. During this swinging, 50

the breech assembly is yieldably supported in the direction of closure by a spring 23 (see Fig. 2) secured to the body of the gun barrel. This spring is preferably so dimensioned that it is capable of counterbalancing the weight of the breech assembly when the breech action involves vertical movement of this assembly. The course and velocity of the breech-opening motion can be varied within wide limits by varying the shape of the cam groove 22.

5 The breech nut 10 is provided with teeth 24 adapted to be engaged by corresponding teeth 24' on the hollow screw spindle extension 27 of the plate 19 when the breech is closed (see Figs. 1 and 5). This arrangement constitutes a dog clutch for a temporarily restricted driving of the breech nut, the mode of operation being as follows: When the breech is closed the said clutch 24, 24' is in full engagement. On opening, that 10 is to say when the plate 19 is rotated, the dog clutch first causes the breech nut 10 to be rotated along with the plate 19, with the result that the spindle 11 becomes axially displaced rearwardly in this nut, and the tight closure of the 15 gun barrel is thus relieved. Since, however, the breech nut 10 does not move axially while on the other hand the plate 19 does move back during rotation, a point is reached when the dog clutch 24, 24' comes out of engagement. From 20 this moment on, for the rest of the opening action, the breech nut 10 is held fast against rotation by the frictional resistance between this nut and the holder sleeve 12. At the same moment the projecting pin 18 of the lever 17 engages the 25 cam portion of the guide groove 22, with the result that the rocking shaft 15 and the hub 12' are bodily pivoted, thereby swinging the breech assembly from the axial position into a position in which the loading aperture is fully disclosed, 30 that is to say in which the breech is opened.

35 In closing the breech, the reverse procedure takes place, the crucial point being that at which the dog clutch 24' is re-engaged. Since there is no extrinsic reason for rotation of the breech nut 10, which is held fast by friction, the teeth 24, 24' of the dog clutch return automatically 40 into the same relative positions which they occupied at the moment of disengagement.

45 A modified form of construction of the invention is shown in Figs. 4 and 6. The threading 50

for the supporting spindle 27 is cut directly in the body of the gun barrel 16. This supporting spindle 27 is hollow and provides an aperture through which loading is effected. Thus the spindle 27 rotates in a fixed nut 21 and moves thereby axially. To the rear this spindle is expanded to form the plate 19 fitted with a crank-handle and provided with the cam groove 22 for the controlling and operation of the squared rocking member 13 which projects through a 10 hub of square cross-section, said hub being integral with the breech block 26. The supporting spindle 27 effects the pressing of the breech-block 26 into the position of closure. The breech-block consists of a sufficiently ruggedly dimensioned disc which closes the end of the barrel 16 in the axial position, through being pressed up by the hollow supporting spindle 27.

15

In opening, the disc 26 is slackened back by virtue of the fact that the supporting spindle 20 travels back and takes the disc with it by means of an overhanging rim 25 of semicircular shape engaging with an annular flange 26' on the breech block 26. The rocking member 13 is connected with the lever 17 which is provided 25 with a pin 18 engaging in the cam groove 22 of the cam plate. These parts are so proportioned and the cam groove 22 is so arranged that as soon as the breech-block 26 has been sufficiently retracted in the breech-opening operation, the pin 18 of the lever 17 on the outer 30 end of the rocking member 13 comes into engagement with the cam portion of the control groove 22, whereupon the rocking member 13 is pivoted and swings the breech-block 26 into 35 the open position.

35 I claim:

In a gun, a breech block, a rotatable cam plate mounted coaxially with the gun barrel, and means operable upon rotation of said plate 40 for automatically effecting, in succession, an axial movement of the breech block and an arcuate lateral bodily movement thereof, said plate having a cam groove therein, and said means including a rocking member eccentrically journaled in the gun barrel, means connecting said rocking member with said breech block, and a crank pin on said rocking member serving as a cam follower and riding in said cam groove.

JAROSLAV HÁSEK.
